DRAINAGE FITTING

Filed Dec. 10, 1930

INVENTOR.
EDWARD W. N. BOOSEY

BY

Wm. E. Wiener
ATTORNEY.

UNITED STATES PATENT OFFICE

EDWARD W. N. BOOSEY, OF DETROIT, MICHIGAN

DRAINAGE FITTING

Application filed December 10, 1930. Serial No. 501,453.

This invention relates to drainage fittings and the object of the invention is to provide a drainage fitting in which the drain head is adjustable vertically to accommodate the fitting for use with floors of different thicknesses.

Another object of the invention is to provide a device of the character described in which any seepage through the floor or about the drainage fitting is carried into the drain.

Another object of the invention is to provide a drainage fitting having seepage rings through which any water passing through the floor seeps into the drain pipe, the drain itself being constructed to drain water from the floor surface directly therethrough.

These objects and the several novel features of the invention are hereinafter more fully described and claimed and the preferred form of construction by which these objects are attained is shown in the accompanying drawing in which—

Fig. 1 is a vertical section through a drainage fitting embodying my invention.

Fig. 2 is a section taken on line 2—2 of Fig. 1.

Fig. 3 is an elevation of the adjusting ring by which the height of the upper end of the drain is adjusted.

The drain comprises a drain pipe 1, shown in Fig. 1, having an annular chamber 2 about the upper end thereof and a flange 3 extending outwardly from the chamber wall. This flange 3 is provided with a rounded shoulder 4 and a lead flashing 5 is laid over this shoulder and extends into the annular chamber 2 as shown. The lead flashing 5 extends outwardly about the drain fitting and may extend through or beneath the entire floor in which the drainage fitting is mounted. The annular chamber 2 is filled with caulking 6 to hold the inner edge of the lead flashing 5 in place and to prevent the annular chamber 2 from filling with water. The upper end of the drain comprises a tubular member 7 of smaller diameter than the diameter of the drain pipe 1 and this tubular member, as shown in Fig. 2, is provided with three vertical ribs 8 fitting within the drain pipe 1. At the upper end the member 7 is provided

with a drain head comprising a flange 9 having an upwardly extending flange 10 to which the drain plate 11 is secured by the screws 12. An adjusting ring 13 is positioned about the tubular member 7 and is provided with a set screw 14 by means of which the ring 13 may be secured at any point on the tubular member 7. This ring 13 is provided with three lugs 15 on the bottom adapted to rest on the upper edge of the drain pipe 1 and space the ring from the upper edge of the said drain pipe. The ring 13 is provided with an annular recess 16 therein and a seepage ring 17 is positioned in this recess and fits about the tubular member 7. The upper edge of the drain pipe 1 is provided with an annular recess 18 and a seepage ring 19 is positioned in this recess and fits about the tubular member 7. These seepage rings are formed of felt or other flexible absorbent material and therefore readily fit about the tubular member 7 and are sufficiently yieldable as to fit over the vertical ribs 8 thereon. By loosening the set screw 14 the upper end of the drain may be adjusted so that the drain plate 11 will extend flush with the floor surface when the floor is laid. This drain is excellently adapted for use in concrete floors as the upper end of the drain may be adjusted while the floor is being laid and the concrete may then be laid thereabout. After the upper end of the drain has been adjusted to the proper position the set screw 14 is turned up tightly to fix the ring 13 in position and this ring then supports the upper end of the drain on the upper edge of the drain pipe 1. If there is any seepage through the floor it collects on the flashing 5 and is carried inwardly thereby and passes through the space 20 between the upper edge of the drain pipe 1 and the spaced lower edge of the ring 13. This water then seeps through the seepage ring 18 and through the space between the drain pipe 1 and the tubular member 7 so that the seepage thus flows into the drain. If there is any seepage about the tubular member 7 it flows into the space 21 between the ring 13 and the member 7 and through the seepage ring 17 and thence through the seepage ring 19 into the drain. By this arrangement the seepage

is always carried into the drain and the surface drainage passes through the drain plate 11 and member 7 directly into the drain pipe 1.

- 5 From the foregoing description it becomes evident that the device is very simple and efficient in operation, provides a drainage fitting which may be adjusted to various floor thicknesses, will carry off the seepage as well 10 as surface drainage and provides a device which accomplishes the objects described.

Having thus fully described my invention, its utility and mode of operation, what I claim and desire to secure by Letters Patent 15 of the United States is—

1. In a drainage fitting, a drain pipe, a drainage head including a depending tubular portion having an imperforate wall, a series of vertical ribs on the exterior of the said 20 tubular portion, an adjusting ring adjustably secured to the tubular portion and extending about the said ribs, a seepage ring carried by the adjusting ring and fitting about the said tubular portion and ribs, the lower end 25 of the tubular portion being adapted to be inserted in the upper end of the drain pipe in spaced relation with the wall thereof and the adjusting ring being provided with a series of lugs on the lower side supporting the 30 drain head and tubular portion on the upper end of the drain pipe and spacing the adjusting ring from the upper edge of the drain pipe.

2. A drainage fitting comprising a drain 35 pipe having an annular chamber about the upper end, a flashing extending into the said chamber, the said chamber being adapted to be filled with caulk to the top of the drain pipe to secure the flashing therein, a drain 40 head including a tubular depending portion having an imperforate wall provided with vertical ribs extending into the drain pipe, an adjusting ring adjustably secured about the tubular portion and resting on the upper 45 end of the drain pipe, a seepage ring carried by the adjusting ring and fitting about the said tubular portion and a seepage ring carried by the upper end of the drain pipe and fitting about the said tubular portion.

- 50 3. In a drainage fitting, a drain pipe, a drainage head having a depending tubular portion fitting within the drain pipe, the outer diameter of the tubular portion being less than the inner diameter of the drain pipe 55 thereby providing a passageway for fluid between said tubular portion and the drain pipe, an adjusting ring adjustably secured about the tubular portion and in spaced relation therewith, a series of lugs on the lower side 60 of the adjusting ring resting on the upper end of the drain pipe and spacing the adjusting ring therefrom, and a seepage ring carried by the upper end of the drain pipe and fitting about the said tubular portion.

- 65 4. A drainage fitting comprising a drain

pipe, a drainage head having a depending tubular portion provided with vertical ribs on the exterior and fitting within the upper end of the drain pipe, an adjusting ring adjustably secured about the said tubular portion and resting on the upper end of the drain pipe and a seepage ring carried by the adjusting ring and fitting about the said tubular portion through which fluid may pass to between said tubular portion and the drain 75 pipe.

5. In a drainage fitting, a drain pipe, a drainage head having a depending tubular portion fitting within the drain pipe, the outer diameter of the tubular portion being 80 less than the inner diameter of the drain pipe providing a passageway therebetween, an adjusting ring secured about the drain pipe in spaced relation therewith and supporting the drain head on the upper end of 85 the drain pipe, and a seepage ring carried by the upper end of the drain pipe and fitting about the said tubular portion through which fluid may pass to said passageway.

In testimony whereof I sign this specification.

EDWARD W. N. BOOSEY.
